Primary Examiner — Deanna L Pratt

(57) **CLAIM**

The ornamental design for a cladding for forklifts, as shown and described.

DESCRIPTION

The patent or application file contains at least one drawing executed in color. Copies of this patent or patent application publication with color drawing(s) will be provided by the Office upon request and payment of the necessary fee.

FIG. 1.1 is front-side, right-side perspective view of the cladding for forklifts showing my new design.

1 Claim, 1 Drawing Sheet
